UNITED STATES PATENT OFFICE.

JOHN BEAN AND ROSCOE BEAN, OF SPRINGFIELD, OHIO.

HOBBY-HORSE.

SPECIFICATION forming part of Letters Patent No. 284,940, dated September 11, 1883.

Application filed June 9, 1883. (No model.)

To all whom it may concern:

Be it known that we, JOHN BEAN and ROSCOE BEAN, citizens of the United States, residing at Springfield, in the county of Clarke and State of Ohio, have invented certain new and useful Improvements in Hobby-Horses, of which the following is a specification, reference being had therein to the accompanying drawings, in which—

10 Figure 1 is a pipe (tubular) frame-work, adapted to sustain and support our rocker or hobby horse. Fig. 2 is a perspective view of our improved device. Fig. 3 is a vertical transverse section through the device in line $x-x$.
15 Fig. 4 is a modification of our invention, showing the seat swung by springs. Fig. 5 is a cross-section showing the connection of the two cheek-pieces (which may be in the form of horses) and the rear suspension bars or springs.
20 This invention has for its object to provide, first, a light and substantial frame for supporting a child's hobby-horse, sleigh, or any other figure to enable the child to rock or swing freely to and fro, and to so construct
25 the frame and seat with its appurtenances that the same can be readily taken apart for packing in a small compass, and with equal readiness put together again, as will be fully understood from the following description, when
30 taken in connection with the annexed drawings.

The supporting-frame of our device is preferably made of gas-pipe, because it is light and can be made up of small pieces. The
35 legs A A have T-shaped feet B B, and the upper ends of these legs, which are connected to a U-shaped frame, having secured on the ends of the limbs of this frame T-pieces C C. We prefer to use T-couplings for connecting
40 the joints of the sections, made so that they act as set-screws to firmly hold the parts together, at the same time admitting of their detachment when it is desired to pack them for transportation.

45 The frame which we have above described is light and substantial, and easily put together and taken apart. It presents two upwardly-extended limbs, on which are the rigid cross-pieces a a. From the ends of these cross-pieces
50 depend hangers D D D D, to the lower ends

of which are suitably secured the cheek or side pieces, E E, of a seat, F, a foot-piece, G, and a cross-piece, H. The hangers can be made of elastic material, strips of leather answering well, which may be rigidly secured at 55 each end. The cheek-pieces may be in the form of horses, the front and hind feet of which are connected in a suitable manner to the swinging-springs D. Any other figure may be adopted in lieu of the horses to represent the 60 cheek-pieces, to which the seat and foot-board are attached. We secure the parts composing this swinging seat-frame together by means of screws, so that they can be readily detached or put together again. The whole structure is 65 commonly known as a "knockdown piece," and the frame may be made of pipe, as above described, of solid rods, coupled together in sections, or of wood.

Instead of having the bow below the swinging seat, it may be arched over the seat-frame, (or horse.)

It is obvious that by making the cheek-pieces separate and connecting them as we have above described they can be depressed lower 75 than if there was a solid piece, for the reason that the lower portions of these cheek-pieces are astride of the inverted bow. The cheek-pieces, whether they be the contour of horses or of any other shape, are secured to the seat, 80 the foot-piece, and to the hand or breast piece by means of screws or the equivalents thereof, which can be easily removed, thus affording a knockdown frame.

It will be seen that the invention which we 85 have above described consists, essentially, of a seat or cradle, which may be ornamented in any fancy manner, and that it will swing either longitudinally, or, if springs be applied to the hangers, it will swing both longitudinally and 90 laterally, suspended from the longitudinal bow of the light supporting-frame.

It is obvious that the couplings which connect the joints or sections of the frame together may be locked in a manner similar to the same 95 couplings which we use on our patents for wheelbarrows, granted in the year 1882, or in any other suitable manner.

The springs, which we now letter S, are rigidly fastened at each end, and as a child in the 100

seat swings these springs have a tendency at all times to bring the seat nearer to the center of motion.

One of the leading features of our invention is the tubular frame-work, put together with ⁵ **T**-couplings, adapted to slip over the pipe-sections, and **T**-pieces screwed in to form set-screws. At the end of the pipes, where they screw into the couplings or crosses, we may ¹⁰ use a loose disk, which extends into the ends of the pipes and helps to hold the parts firmly.

Another leading feature is the springs, fastened ¹⁵ at each end, so that as the child swings they have a tendency to bring the seat nearer the center.

Another feature of our invention is making the horses in separate pieces, so that the same can be detached and packed in a small space for transportation.

If desired, instead of having cross-pieces ²⁰ at the ends of the frame-work, we can secure these supporting-pieces at other places on this frame. The sliding couplings, or crosses, if made in the form of crosses, are made with ²⁵ openings on two sides to allow said pieces to be screwed in and form set-screws on each or on two sides. The sliding couplings have **T**-openings, and in these openings we put a loose button, pointed on one side. After ³⁰ sliding these couplings to their proper places, we put in the loose buttons and screw the cross-arms or legs into the sliding couplings. By screwing up the legs or cross-arms it presses the pointed button into the pipe and ³⁵ secures them rigidly to the desired position, forming set-screws. These loose buttons may be used or not; but we find that the frame-work holds better when they are used. The main piece of the frame-work we find is preferably made of one piece, either of wood or ⁴⁰ iron. The cross-arms are round where the springs or straps are fastened, and the latter are fastened in such manner that as the seat moves back and forward these springs roll and ⁴⁵ unroll on this cross-piece. At the lower ends of the straps we also make the pieces to which the straps are attached round, to allow them to roll and unroll. By this arrangement the springs are not liable to break by use, and the ⁵⁰ seat is allowed to swing easily. The springs are not necessarily attached at the ends of the feet or legs; but cross-pieces can be attached at any convenient place on the seat-supporting pieces. The pendants are all elastic, but ⁵⁵ secured rigidly at each end, so as to have a direct forward and backward motion.

Having described our invention, what we claim as new, and desire to secure by Letters Patent, is—

60 1. A frame for a swinging seat, consisting of standards having **T**-shaped feet and a **U**-shaped section having cross-heads, substantially as described.

2. A sectional frame for a swinging seat, ⁶⁵ composed of a bow having cross-heads and

supporting-legs having feet, the sections composing such frame being connected together by screw-couplings, all constructed and adapted to operate substantially in the manner and for the purposes described. ⁷⁰

3. The combination of a bow-shaped frame, angular arms fixed to the extremities thereof, inclined legs rigidly secured by **T**-shaped couplings thereto, and foot-pieces, also rigidly secured to said legs, substantially in the ⁷⁵ manner and for the purposes described.

4. The combination of a frame which is composed of a bow-brace, transverse pendants, and supporting-legs, of pendants swung from the said transverse arms, cheek-pieces attached to said arms, and a seat secured to said cheek-pieces, substantially as described. ⁸⁰

5. The combination of the bowed suspension-frame provided with supporting-legs, of the transverse bars, the suspension-arms, the ⁸⁵ cheek-pieces, supported at their lower extremities by said arms, a seat, a foot-piece, and a connecting-brace rigidly but removably applied to said arms, all constructed and adapted to operate substantially in the manner ⁹⁰ and for the purposes described.

6. The combination of a sustaining bow or arch, legs and feet therefor, composed of gas-pipe coupled at the joints by **T**'s, and a ⁹⁵ swinging seat depending from the ends of said bow, all constructed and adapted to operate substantially in the manner and for the purposes described.

7. In combination with a frame which is composed of a rod bent in the form of a bow and having cross-pieces, spring-suspenders, and a seat applied to these suspenders, substantially as described. ¹⁰⁰

8. As a new and improved article of manufacture, a supporting-frame consisting of a bowed rod and transverse sustaining portions, suspension-rods rigidly attached at each end, separated cheek-pieces, an intermediate seat secured thereto, and a connecting-brace, all constructed and adapted to operate ¹⁰⁵ substantially in the manner described.

9. In a hobby-horse and articles of like kind, the frame-work having movable couplings and held in position by cross-arms, forming set-screws, for the purpose specified. ¹¹⁵

10. In a hobby-horse, the frame-work having movable couplings thereon, in combination with cross pieces or legs secured in said couplings, and an interposed button between the end of said pieces and the frame, for the ¹²⁰ purpose specified.

11. The combination of cheek-pieces and seat, constructed to be easily separated and put together, also constructed to allow the frame-work to pass through the body above the legs, ¹²⁵ for the purpose specified.

12. In a hobby-horse or other article of like kind, a stationary frame resting below and supports secured near the upper end of the frame and near the lower end of the horse, ¹³⁰

when said supports are rigidly secured at both ends, substantially as and for the purposes specified.

13. As a new article of manufacture, a frame-work resting below two swinging separate cheek-pieces, arranged with a seat or saddle above and stirrups at the sides, to enable the rider to ride astride, substantially as specified.

In testimony whereof we affix our signatures in presence of two witnesses.
